CUTTING AND SCRAPING DEVICE

Herman F. Sieg, Pittsburgh, Pa.

Application October 17, 1940, Serial No. 361,486

2 Claims. (Cl. 30—338)

My present invention relates to a cutting and scraping device, and particularly to a sheet metal holder adapted to receive a razor blade and to form therewith a convenient, simple and inexpensive means for removing adhering materials such as paper, adhesive, etc. from glass, wall, wood and other surfaces.

Devices are at present available which hold razor blades and which form devices of the same general type or character as that forming the basis for my present invention. Such devices, while reasonably satisfactory, are far from being ideal or foolproof in their construction and leave much to be desired in the way of length of life, safety in use and versatility of applicability. Most razor blade holders embody parts which are difficult to keep clean or sterile and which usually involve the use of screw shafts and nuts for tightening and clamping purposes. Many of the devices of this nature which are intended for use with double-edged blades having openings through the body thereof require special lugs or projections to be formed on or in the holder in order to secure even reasonably firm positioning of the blade. These holders are only adapted for use with one specific type of blade. They are especially characterized by the fact that they frequently cannot be used in narrow or cramped spaces and must always be used on only one side due to the projecting screws, nuts, etc. on the other side and which would undesirably scratch, score or otherwise mar the surfaces being worked upon. It is thus apparent that there is no device available or known which meets all the requirements of a commercial article of this character.

One of the objects of the present invention is to produce a cutter and scraper which is capable of receiving and utilizing any form of razor blade, whether of the single or the double-edged type.

Another object of the invention resides in providing a cutting and scraping device which can be used from either side without marring the surface which is being worked upon, whether the same be glass, metal, wood or other material.

A further object of the invention resides in producing a cutter and scraper which can be manufactured at a nominal cost and which can therefore be sold in the five and ten cent stores or other chain stores for a price considerably below that at which existing holders are sold.

A still further object of the invention resides in providing a cutter and scraper in which a razor blade can be firmly and adequately held and positioned during the cutting or scraping

operation and yet without providing extra or special projections, screw parts, etc. in or upon the device itself.

Other and further objects and advantages will be understood by those skilled in this art or will be apparent or pointed out hereinafter.

In the accompanying drawing I have illustrated a device embodying my present invention:

Fig. 1 is a plan view of an embodiment of the invention showing a double-edged blade in operative position therein;

Fig. 2 is an edge elevational view of the device of Fig. 1; and

Fig. 3 is a fragmentary, enlarged, disassembled perspective view of the blade-holding portion of the device of Figs. 1 and 2, modified by a supplemental interengaging means.

Similar numerals designate corresponding parts throughout the several views of the drawing.

The device of this invention broadly includes a member which has parts adapted to be contracted or compressed into engagement with a razor blade, parts engaging such blade and means for holding such parts in operative association under such conditions that simple and ready disassembly is made possible.

The device of this invention can be produced at a very low cost and in a very simple manner. A suitable strip or sheet of metal of the desired gage, composition and physical characteristics is stamped, die cut or otherwise shaped or formed into the configuration illustrated. As so produced, the device comprises two substantially parallel arms 20 of sheet metal connected at adjacent ends by a simple, U-shaped bent or curved portion 21. This portion, as well as the nature of the metal itself, contributes the necessary springiness or resiliency which is required therein. Near their forward or blade-holding ends the arms 20 converge rapidly as at 22, beyond which they again become substantially parallel, forming transition portions which connect the arms 20 and the holding portions 23.

As will best be appreciated by a reference to Fig. 3, one arm 20 is provided with a T-shaped opening 24 just rearwardly of the terminus of the main parallel portion thereof. This T-shaped slot has its cross-bar portion 25 disposed across the arm, i. e., the major axis thereof is at right angles to the major axis of the arm itself. Therefore, the stem portion 26 of the T-shaped slot is parallel to the arm 20 itself. It will be particularly noted that the more or less triangular metal portions 27 lying on either side of the stem 26 and below the extensions of the cross-bar portion

25 of the slot 24 are depressed, being bent inwardly and downwardly and therefore forming a depressed seat, the purpose of which will be explained hereinafter. Viewed from the side, as in Fig. 2, it will be noted that this seat is below the level of the arm and is inclined upwardly from front to rear, i. e., toward the blade-holding portion of the arm. The terminus of this arm is a flat marginal portion 28 which is connected by a concavo-convex portion 29 to a somewhat raised or offset rearward marginal portion 30 which is unitary with the transition portion heretofore mentioned.

The other arm 20 is provided with a struck-up T-shaped locking element 31 which rises substantially vertically from such arm. A trapezoidal opening 32 is thereby formed in such arm as a result of the removal of material therefrom for the formation of the element 31, the opening 32 being a trapezoid rather than T-shaped due to the fact that it is generally preferable from a production or mechanical point of view to strike up an initially trapezoidal piece and then to shape or notch out the same to produce a T-shaped element. The terminus of this arm is so configured as to provide a complementary flat marginal portion 33 adapted to form with the marginal portion 28 of the other arm a pair of jaws or pincers. The lateral ends of this portion 33 are, however, bent upwardly at right angles to provide short lateral upstanding flanges 34, the distance between the inner sides of which is only slightly greater than the length of the said marginal portion 28. The arm terminus is further provided with a concavo-convex intermediate portion 35, which, however, is the reverse of that of 29 so that the concave sides of these two portions face each other and the convex sides are accordingly on the outside surfaces of the pincers. This portion of arm 20 has a rearward marginal portion 36 which is somewhat dished or depressed in a direction opposite in curvature to the portion 33 already mentioned so that in the contacting positions of portions 28 and 33 a more or less uniform space is formed within which is adapted to be received and gripped the thickened edge of a single-edged blade. The ends of portion 36 are flanged at 37. The rearward edge of the arm terminus is provided with the spaced upstanding flanges 38 which form a stop or limiting barrier as well as a guard. Portions 29 and 35 will, under these conditions, engage the forward edges of stiffener 13, thus immobilizing the blade. Part 28 is preferably and optionally provided with projections 28a which are adapted to seat in the notches 34a in part 34 and thus form a positive interengaging supplemental means.

This device is capable of utilizing any known form of razor blade. In using the single-edged type of blade, the pincers are separated and the blade placed in such position that the stiffener 13 thereof lies in the space which is formed between the portions 39 and 36, the two arms being moved toward each other by a gentle gripping or squeezing action and until the locking bar 39 of the T-shaped projection 31 passes through the portion 25 of the T-shaped slot 24 in the other arm, whereupon the said locking element moves forwardly and bar 39 seats itself on the depressed seat already described. The parts are so constructed and arranged that the tendency is for

the locking member to move forwardly to the narrow portion described and to seat itself as described. In this condition the device is ready for use, and by observing Fig. 2 especially it will be noted that there is little or no projection of the locking element above the surface of the slotted arm. Thus the device can be employed without respect to a top or bottom, thereby enabling the objects and advantages hereinabove set forth to be achieved. The insertion of a double-edged blade is the same as that described for a single-edged blade, and it will be apparent that in employing a double-edged type of blade the blade is inserted until it abuts the spaced flanges 38 on the rearward edge of the portion 23 and that the portions 28 and 33 engage the same and hold it sufficiently firmly for the desired cutting, scraping or other operations. The flanges 34 prevent side slip of all types of blades and the flanges 38 act as guards to prevent inadvertent damage by the rearward edge of a double-edged blade.

It will be appreciated that the foregoing is intended as illustrative and not as limitative and that within the scope and purview hereof other and further additions, omissions, substitutions and modifications may be made. The invention is rather to be measured by the appended claims.

Having thus described my invention, what I claim as new and desire to secure by Letters Patents is:

1. A cutting and scraping device composed of a pair of generally parallel arms connected at one end by a suitable unitary bend and converging at their distal ends to form a pincer-like portion, said arms having interengaging portions formed therein for maintaining the pincer-like portion in a condition which is adapted to immobilize a suitable cutting and scraping element when placed therein, said interengaging portions including a T-shaped slot in one arm and a substantially T-shaped projection in the other arm, said slot being so formed that its cross-bar portion is transverse to the major axis of its arm and the triangular portions between the bar extensions and the stem thereof are inwardly and downwardly shaped to form a seat below the level of said arm.

2. A cutting and scraping device composed of sheet metal having a body portion composed of a pair of substantially parallel arms connected at one end by a sheet metal bend and having their distal ends formed to provide a pincer-like portion for receiving and holding a razor blade, said pincer-like portion being made up of a pair of elements one of which is provided with a flat marginal portion, a rearward offset marginal portion and a concavo-convex intermediate portion, convex side outward, and the other of which is provided with a flat marginal portion each end of which is bent over to provide an end flange, a rearward marginal portion having spaced upstanding flanges on its rearward edge and a concavo-convex intermediate portion therebetween, convex side outward, thereby forming when said members are in contact a recess for the admission of a blade-stiffening element and guard means for preventing undesired rearward or lateral movement of such element.
